TYPEWRITING MACHINE

Jesse A. B. Smith, Stamford, Conn., assignor to
 Underwood Elliott Fisher Company, New York,
 N. Y., a corporation of Delaware

Application April 22, 1933, Serial No. 667,324

10 Claims. (Cl. 197—126)

This invention relates to manifolding devices for typing machines, and particularly to improvements in a manifolding device of the character seen in Patent No. 1,801,496, to J. S. Fleming, dated April 21, 1931.

In said Fleming device, carbons, used between the plies of a continuous work-web, extend in the form of tabs beyond the lateral edges of the work-web, the tabs being united by stitching, so that 5 the carbons are jointly holdable while the web is advanced relatively to the carbon-pack. The lengthened outer ply of carbon is folded up at the bottom to form a loop. Said loop co-operates with a stationary blade, in front of the 10 platen and extending transversely of the pack, between the fold-forming plies, to hold the pack still when the work-web alone is to be advanced. After typing a set of work-forms, the web and 15 carbon-pack are advanced together until the transverse loop of the pack strikes said blade. The blade is then, by means of the loop, enabled to hold the carbon pack stationary while the web alone is further advanced to bring a fresh set of 20 work-forms into register with the carbons and to also bring the typed set of forms beyond the carbons, so that they may be severed.

The carbon-arresting blade has heretofore been permanently fastened at each end to the back of a retaining bar mounted in proximity to 25 the printing line of the platen. The blade was disposed in juxtaposition to the back of said retaining bar, being separated therefrom by just enough space to permit threading, upwardly through said space, of the outer one of the loop-forming plies of the carbon-pack, together with 30 any overlying ply of the work-web which may course through said space. The blade-retaining bar was detachably mounted at its ends in the platen-frame, so that both the bar and the blade 35 fastened thereto could be lifted out clear of the platen. It was necessary not only to thread the plies through said space, but to also lift the bar and attached blade away from the platen, to a 40 convenient position, in order that threading might be done from the bottom of the space. After the threading operation, the bar and attached blade, with the plies threaded therebetween, had to be replaced with time-consuming care, to avoid buckling or scuffing of the threaded 45 plies.

In threading plies coated with carbon through 50 said space, the typist's fingers are likely to become smudged. Moreover, since the space between the blade and the bar is constricted, as explained, the threading has to be done carefully,

and hence it is not an operation that can be done with celerity. These disadvantages are particularly objectionable where, as in varying work-routine, the typist must frequently take one web out of the machine and replace another web therein. Each web may be threaded as usual into its individual carbon-pack, so that, when webs are changed, an additional interchange with respect to a common carbon-pack is avoided.

It is an object of the present invention to provide for ease and celerity in the removal from 10 and introduction to the typing machine of a multiple-ply web preassembled with a Fleming-type carbon-pack.

To this end, a carbon-arresting blade is provided which may be readily withdrawn from the path of the composite web. A gap is left between the retaining bar and the platen so that a web and its carbon-pack, introduced in the usual way, at the back or intake side of the platen, may 15 readily pass their leading edges through and beyond said gap. The outer one of the loop-forming carbon-pack plies may be then temporarily held forward, to open the web for replacement of the carbon-arresting blade behind 20 said outer ply, so that it may co-operate with the aforesaid loop. Thus there is no threading of web-plies through a narrow space. Yet, as heretofore, said blade may be close to the back of the retaining bar so as to compact the parts, and, 25 furthermore, so that the retaining bar may aid in minimizing the tendency of the loop-forming carbon-pack plies to slip around the blade when the web is being advanced while the pack is being held by said blade.

The blade-retaining bar may also serve as a web-severing knife which is another reason for keeping the blade close to said bar since the webshearing operation is thereby facilitated.

In practicing the invention, the carbon-arresting blade, normally standing on edge in horizontal position, in front of the platen, is hinged at one end to the retaining or knife-bar at a point at the side of the web-path, to enable said blade to be withdrawn. A novel releasable catch 40 is provided to hold the other end of the blade when the latter is in normal horizontal position. The blade, when released, may be swung about its hinge, laterally away from the web-path, preparatory to removing a web, or to introducing 45 a web and carbon-pack through the gap between the blade-retaining bar and the platen.

The composite web, after its introduction 50 around the platen, is opened for the replacement of the arresting blade by swinging the outer car-

bon-pack loop-forming leaf temporarily forward, whereupon the blade is swung back into position behind said leaf and held by the catch to lie in the path of the aforesaid loop.

5 The catch is arranged so that as the blade-end is seated therein the blade becomes automatically locked. The catch is further arranged so that a slight deflective movement of the locked blade-end, by means of a finger-piece on the blade, is sufficient to release the blade from the catch.

10 Inexpensive paper usually constitutes the continuous web-plies from which the typed forms are severed to serve as office records. These records may be duplicates of bills or statements sent out 15 to customers. In order that the customer's bill-sheet may be of a better grade of paper, a separate sheet of paper is employed for the bill.

In order that the separate bill, for simultaneous typing with the record-web, may be quickly 20 collated with said web, it is contrived to provide the carbon-pack itself with a collating gage against which the lower edge of the separate bill-sheet may be presented, the carbon-pack being 25 disengaged to collating position by means of its described loop and the aforesaid blade. The web-form may be collated relatively to the collated carbon-pack position either by means of an external gage or by means of registering it with some convenient portion of the carbon-pack.

30 The novel bill-collating gage on the web-supported carbon-pack may be in the form of a flange or ridge projecting from the face of the pack near the lower edge of the latter. To this end, there may be a strip having a longitudinal bend or 35 fold. The portion on one side of the strip-fold may be attached to the back of the inner loop-forming carbon-pack ply with the fold below the carbon-pack loop, so that the portion on the other side of the fold may jut forwardly to form the 40 sheet-gaging flange or ridge. The strip may, moreover, be made of resilient material, so that the bend or fold constitutes a hinge, whereby said forwardly-jutting gaging portion may be made to lie flat against the pack, when, instead of a 45 separate bill being used, the outer carbon-pack ply is interleaved with the web.

Other features and advantages will hereinafter appear.

In the accompanying drawings,

50 Figure 1 is a perspective view of a platen-frame illustrating a web and carbon-pack in place, around the platen, and also showing the novel blade and retaining bar organization and the novel collating gage on the web-riding pack.

55 Figure 2 is a fragmentary cross-section view through the platen, showing particularly how the sheet-collating gage may be folded against the pack when covered by an outer web-ply which may be used instead of the separate sheet.

60 Figure 3 is a fragmentary side-section view through the blade-supporting bar to illustrate details of the blade-catch.

Figure 4 is a perspective view illustrating how the web, positioned around the platen, may be 65 opened between the loop-forming leaves for ready insertion between said leaves of the swingable carbon-pack-arresting blade.

70 Figure 5 is a perspective view of the carbon-pack to illustrate the application of the novel sheet-collating gage thereto.

75 Figure 6 is a cross-section view through the platen, showing how the carbon-pack is arrested by the abutment of its described loop with the blade and also showing how an outer bill-sheet

may be collated by means of the novel gage provided on the carbon-pack.

Figure 7 is a fragmentary perspective view of the novel catch for the blade and shows particularly how the blade may be deflected for release from said catch.

The invention is illustrated in connection with an Underwood platen-frame which includes end plates 10 and a rear-insertion paper-table 11. A platen-axle 12, journaled in the end plates 10, carries a revoluble platen 13, against which types 14 strike. Co-operating with the platen are bottom feed-rolls 16 and 17.

Figure 1 shows a multiple-ply continuous work-web 19 in working position around the platen. 15 Interleaved with individual plies 20 of the work-web 19 is a carbon-pack 21, shown separately in Figure 5. Said carbon-pack 21 includes individual carbon-sheets 22, having at their lower portions lateral tabs 23. The two foremost plies 24 20 and 25 of the pack are connected at the bottom to form a loop 26 and only the inner ply 25 has the tabs 23 for union with the other sheets 22, all the tabs 23 at each side of the pack being united by a row of stitching 27 which clears the 25 side of the work-web 19 when the latter is threaded into the carbon-pack 21. The inner plies 22 of the pack have their bottom edges folded for re-inforcement as at 28. The lower edges of the carbon-pack have the overlapping arrangements seen in Figure 6, so as to facilitate introduction of the individual plies 20 of the work-web 30 between the carbons.

The web 19 is threaded into the carbon-pack 21 before the web is introduced, from the rear, 35 between the platen 13 and the paper-table 11. The leading edges of the composite web then passing between the platen 13 and lower feed-rolls 16, 11, emerge at the front of the platen and continue upwardly to pass easily through a 40 gap formed between the platen and a web-severing knife-bar 30 extending parallel to the platen, above the printing line. Said bar 30 is secured at its ends to left and right brackets 31, 32, formed as seen in Figure 1, for attachment to 45 the platen-frame side-members 10 by screws 33.

A carbon-pack-arresting blade 34 co-operates with the carbon-pack loop 26 to hold the carbon-pack stationary when it is required to advance the web 19 relatively to the pack as will be described. Said blade 34 is hinged at one end upon a headed pivot 35 which may project rearwardly from a flange 36 of the right-hand bracket 32. As seen in Figure 1, the outer loop-forming ply 24 of the carbon-pack passes between the blade 34 55 and the knife-bar 30.

Instead of threading said outer ply 24 and any overlying ply of the work-web 19 through the narrow space between the knife-bar 30 and carbon-pack-arresting blade 34, a procedure is followed which, according to the present invention, can be carried out with celerity and without annoyance to the operator. According to this new procedure, when a web 19, threaded into the described carbon-pack 21, is to be introduced to the platen-carriage, the blade 34 is first swung about its pivot 35 to the dotted-line position seen in Figure 1, so as to be out of the web-path. When the composite web has been entered far enough so that its leading edges are through the gap between 70 the knife-bar 30 and the platen, as in Figure 4, the web may be opened up between the loop-forming plies 24 and 25 of the pack 21, as seen in Figure 4, to permit the blade 34 to be easily returned to its horizontal position behind the 75

knife-bar 30 and between the loop-forming carbon-pack plies 24 and 25. Thus, without any trouble, the outer loop-forming carbon-pack ply 24 and any overlying work-web ply are quickly disposed in their course within the constricted space between the knife-bar 30 and the blade 34, so that the latter will be in the path of the carbon-pack loop 26.

A novel catch for seating and releasably holding the swinging end of the blade 34 may be arranged on the left-hand bar-supporting bracket 31. A flange 37 of said bracket 31 has at its upper edge a flaring lip 38, Figure 7, which cooperates with a plate 39, also having a flaring upper edge or lip, to form a pocket 40, into which the swinging edge of the blade is easily entered by reason of the flaring lips. The plate 39 is fastened directly to the rear face of the bracket-flange 37 by rivets 41 which also secure the left end of the knife-bar 30 to the front of said flange. The rear face of said bracket-flange 37 is therefore jogged, as at 42, to form the pocket-opening 40. The lower part of the flange is formed as seen in Figure 7 to form a seat 43 for the swinging end of the blade 34. Said seat 43 is formed by an indentation 40a of the flange. By said indentation there is also formed an upper edge 44, to which the jog 42 extends, and under which edge an extension 45 of the swinging end of the blade 34 is forced when said swinging end strikes the seat 43. The blade 34 is thus locked against unintentional upward displacement.

For automatically forcing the blade-extension 45 under the holding edge 44 when the blade strikes said seat 43, the bracket-flange 37 carries a spring 47 secured by a rivet 48 to said flange which is accordingly formed as best seen in Figure 7. The upper portion of said spring has a nose 50 which lies sufficiently in the path of the swinging blade-end to force the latter under the locking edge 44 when the blade rests on the seat 43. As seen in Figure 7, said nose flares rearwardly out of the path of said blade-end extension, so as to yield to the passage of said extension 45 until the latter enters the recess formed between the seat 43 and the locking edge 44. The spring 47 then forces said blade-end extension into said recess which, as seen in Figure 3, is also delimited by the knife-bar 30.

The blade-end extension 45 is, as seen in Figure 7, part of a finger-piece 52 secured to the blade by rivets 53. By means of said finger-piece 52, the blade, at its extension 45, may be pressed rearwardly to overcome the spring 47 and free the blade from the locking edge 44 when said blade is to be swung to the dotted-line position, Figure 1.

A separate bill-sheet 55, Figure 6, is readily collated with the work-web by means of a novel gage incorporated in the described carbon-pack 21. In its preferred form, said gage is a strip 58 having a longitudinal bend or fold 59. As indicated in Figure 6, a strip-portion 60, on one side of the fold 59, is fastened to the rear surface, above the loop 26, of the inner loop-forming ply 25. A strip-portion 61 on the other side of the fold 59 may jut forwardly, as in Figure 6, to serve as a gage for collating the bill-sheet 55.

The sheet-gaging strip 58 may be of flexible resilient material, such as stiff paper. The paper being flexible, the bend or fold 59 acts as a hinge for the forwardly-jutting gage-portion 61, so that the latter may be folded against the underlying carbon-ply 24. Figure 2 shows said gage-portion

61 thus folded against said carbon-ply 24 as when an outer ply 20a of said web overlies said carbon-ply 24 and hence said gage-portion 61. The gaging strip 58 being resilient, the gage-portion 61 tends to spring outwardly when there is no overlying work web or ply and a separate bill-sheet 55 may therefore be readily presented to said gage-portion. By reason of its flexibility, the gage-portion 61 may also readily pass between the feed-rolls 16, 17 and the platen 13. The resiliency of the strip 58 causes said gage-portion 61 to jut forwardly, after passing the lower feed-rolls 16, in the advance of the web. As shown in Figure 6, the composite web has been advanced to the position in which the carbon-pack, by means of its loop 26, is arrested by the blade 34. The gage-portion 61, jutting forwardly because of its resiliency, has, by such advance of the composite web, been caused to underlie the blade-retaining bar 30, instead of passing behind said 20 bar.

The gage-portion 61 need not by its resiliency alone spring completely to the Figure 6 position. It will be evident that a substantially less outward jutting of said gage-portion 61, after the latter passes the feed-roll 16, will cause the leading edge of said gage-portion to be intercepted by the lower edge of the blade-retaining bar 30 in such manner that said gage-portion will be cammed or deflected by said bar 30 to the Figure 6 position. It will be understood that, the bar 30 and blade 34 being relatively positioned as shown, the gage-portion 61 is deflected by said bar 30 in order that the carbon-pack may be advanced sufficiently for its loop 26 to be engaged by said blade 34. It will be further understood therefore that said gage-portion 61 may function as a sheet-gage on the carbon-pack, in the absence of said bar 30.

The gage-strip 58 may, as shown in Figure 5, have its ends 57 included in the lateral stitching 40 27, so as to be secured to the carbon-pack. The portion 60 of said gage-strip 58 may be additionally secured to the back portion of the loop 26, as by gumming or by other transverse stitching. Figure 6 shows how an extra bill-sheet 55 may be 45 collated by presentation against the gage-portion 61 which is in collating position when the carbon-pack carrying said gage-portion 61 is arrested by the blade 34. The new set of work-forms on the work-web is advanced to position for collation with the bill-sheet 55, said position being gaged by bringing the tops of said new work-forms just above the top of the blade-arrested carbon-pack, as shown in Figure 6, in which said work-form tops are represented by the marks 63. 55

The marks 63, Figure 6, also represent the location of the lines along which the typed forms 20b may be severed. Preparatory to the severing operation, the work-web, having been advanced relatively to the carbon-pack, is together with 60 said pack and extra bill-sheet 55 retracted by rotating the platen backward until the lines 63 coincide with the top or shearing edge of the knife-bar 30. To insure their joint retraction the web, carbon-pack, and bill-sheet may be jointly 65 gripped by the operator's hand until the lower feed-rolls engage said pack and bill-sheet.

The knife-bar 30 is secured to the right-hand bracket 32 by rivets 64. Said bar 30, its brackets 31, 32, the carbon-arresting blade and the blade-catch incorporated in the bracket 31 are assembled as a unit which may be readily attached to the platen-frame by screws 33 and which conversely may be readily removed as a unit from said frame. The unitary assembly feature con- 75

duces to economy in marketing and installation.

The loop-forming carbon-ply 24 may be coated with carbon as for manifolding upon another separate sheet 65, which, as shown in Figure 6, may 5 be inserted between the loop-forming plies 24 and 25.

For guiding the work-web there may be at the rear of the platen-frame, at each side of the web, a guide 66, Figure 1, adjustable along a cross-rod 67 mounted in brackets 68 of the platen-frame.

Variations may be resorted to within the scope of the invention, and portions of the improvements may be used without others.

15 Having thus described my invention, I claim:

1. In a typewriting machine having a platen over which a multiple-ply work-form web, threaded through a unitary carbon-pack, travels; a supporting bar spanning the platen and fixedly 20 mounted in proximity thereto, a blade in juxtaposition to the platen-side of said bar, said blade forming an edge co-operative with a transverse fold formed by one of the carbon-pack plies to hold the carbon-pack while the work-web is advanced relatively to said pack, said one carbon-pack ply for this purpose coursing between said 25 bar and the arresting blade, and means mounting and releasably holding said blade so that it may be readily moved out of the web path preparatory to introducing the web and carbons between 30 said fixed supporting bar and the platen, and so that said blade may then be readily replaced behind said one carbon-pack ply while the composite web is temporarily opened at said one carbon-pack ply for said blade replacement.

2. The combination with a revolute platen around which a work-web, threaded into a unitary carbon-pack, may travel, said pack including adjacent plies joined to form a transverse 40 loop, of a web-severing knife extending along the front of the platen, a carbon-stripping blade lying between said knife and the platen, said blade insertable between said carbon-plies to engage said loop and thereby arrest the carbon-pack while 45 the web alone is to be advanced, means hinging said blade at one end, to swing upwardly and to one side out of the web path, leaving clear space between the knife and the platen preparatory to introducing the web, including the carbon-pack, 50 around the platen and quickly advancing the leading portion past the normal blade-position, the web being then opened between said adjacent carbon-plies for swinging the blade back into operative position between said plies; said knife-blade confining the sheets when the stripping 55 blade is in swung-up position, and means releasably supporting said stripping blade at the other end against the upward pull of the carbons during the carbon-stripping operation.

60 3. In a typewriting machine having a platen-frame including side-members, and a revolute platen over which is a multiple-ply work-web, threaded through a unitary carbon-pack, travels; a cross-member arranged at its end-portions for 65 attachment to said frame-side-members, to extend lengthwise of the platen above the printing line, said cross-member being separated from the platen by a gap through which, in the introduction of the web together with the carbon-pack, 70 the leading portion is readily entered, and a blade in juxtaposition to the platen-side of said cross-member, a longitudinal edge of said blade being co-operative with a transverse fold formed by one of the carbons to hold the unitary carbon-pack 75 while the work-web is advanced relatively there-

to, said one carbon for this purpose coursing between said cross-member and said blade, the latter extending transversely of the pack, one end of said blade having a hinging support connected to said cross-member, so as to be swingable laterally out of the web path preparatory to said introduction of the web and carbons, said blade being subsequently swung back behind said one carbon while the composite web is temporarily opened at said one carbon for the blade replacement, means being provided for releasably holding the blade in operative position.

4. A device for arresting a carbon-pack while a work-web is shifted relatively thereto, said pack including an arresting loop formed by a 15 fold extending transversely of one of the carbon-pack plies, said device including a bar arranged for attachment to a typewriting machine, so as to extend lengthwise of, and in proximity to, the platen of the latter, a blade hinged at one 20 end to said bar and paralleling said bar in juxtaposition to the platen-side of the latter for engaging said loop to arrest said pack, the outer portion of the carbon-pack loop coursing, for this purpose, between said bar and blade, and 25 a catch to releasably hold the other end of said blade, said blade when released being swingable about its hinge, away from said bar, for facilitating disposition of said outer loop-portion between said bar and blade.

5. A device for arresting a carbon-pack while a work-web is shifted relatively thereto, said pack including an arresting loop formed by a 30 fold extending transversely of one of the carbon-pack plies, said device including a bar arranged for attachment to a typewriting machine, so as to extend lengthwise of, and in proximity to, the platen of the latter, a blade hinged at one 35 end to said bar and paralleling said bar in juxtaposition to the platen-side of the latter for engaging said loop to arrest said pack, the outer portion of the carbon-pack loop coursing, for this purpose, between said bar and blade, and a catch to releasably hold the other end of said blade, said blade when released being swingable 40 about its hinge, away from said bar, for facilitating disposition of said outer loop-portion between said bar and blade, said catch including a pocket, having a flared entrance, at the platen-side of said bar, one side of said pocket having a 45 recess into which the end of said blade may be forced, so as to become locked, and a spring-pressed nose-piece lying in the path of the swinging blade-end to force the latter into said recess when the same is seated in said pocket.

6. In a web-manifolding typewriting machine, the combination with a revolute platen and a platen-frame having side-members, of a web-severing knife-bar extending lengthwise of and facing the platen in proximity thereto, one end 60 of said knife-bar being attached to one of said side-members, the other end of said bar being attached to the outer face of a platen-confronting flange attached to the other platen-frame side-member, a carbon-pack-arresting blade 65 hinged at one end at the first-mentioned end of said knife-bar, and extending in juxtaposition to the platen-side of said bar, said flange having an inner lateral edge indented to form a recess delimited by said knife-bar to receive the other 70 blade-end, and a spring-pressed nose mounted so as to be disposed in the path of said other blade-end and to permit passage of the latter as the blade is swung about its hinge and to also force said other blade-end into said recess, 75

- 5 said blade being releasable from said recess by a slight deflection preparatory to swinging away from said bar, for quick introduction of a carbon-pack and a work-web threaded therewith between said knife-bar and the platen, said pack including plies forming a transverse loop, and the web being opened at said plies for swinging said blade back therebetween to co-operate with said loop for arresting said pack.
- 10 7. In a web-manifolding machine, the combination with a revoluble platen and a platen-frame having side-members, of a web-severing knife extending along the front of the platen, a carbon-pack-arresting blade between the platen, and the knife and insertable between transverse-loop-forming plies of a carbon-pack assembled with a work-web passing around said platen, means whereby one end of said blade is hinged to one of said frame-side-members so as to swing away from said knife and platen, and a catch for releasably seating the other end of said blade, said hinging means and catch co-operating to support said blade in working position against tension of the carbons at the carbon-stripping 20 operation, said blade and knife being lengthwise of, and in proximity to, the platen beyond the printing line, said catch including a plate-like flange extending from the other platen-frame side-member to coincide with the plane of said 25 blade, said flange being recessed on one face to receive said swingable blade-end, and being provided with a spring-pressed nose for forcing said other blade-end into said recess when said blade is in working position, said knife confining the 30 paper to the platen while the stripping blade is in its swung-up position.
- 35 8. For use in a web-typewriting machine employing a web-riding carbon-pack and having a platen, a carbon-pack-arresting and web-shearing device including a shearing bar having ends arranged for ready attachment to said machine so that said bar faces said platen, a carbon-arresting blade having at one end a hinged connection to said bar, and a catch-device whereby the 40 other end of said blade is releasably held relatively to said bar, said hinged connection and
- 5 catch-device supporting said blade parallel with said bar in juxtaposition to the platen-facing side of the latter, said blade co-operative, for the purpose of arresting a carbon-pack, with a carbon-pack ply coursing between said bar and said blade, said blade swingable about its hinged connection to swing away from said bar for facilitating the disposition of said carbon-pack ply between said bar and blade, said bar, the blade hinged thereto and said catch-device forming 10 a unitary assembly arranged for ready attachment to said machine.
- 15 9. The combination with a revoluble platen and a platen-support, of a web-shearing bar connected at its ends to said platen-support to extend lengthwise of, and in proximity to, the platen, a carbon-pack-arresting blade, and means mounting said blade parallel to the shearing bar and in juxtaposition to the platen-facing side of the latter, said blade being co-operative, for the purpose of arresting a carbon-pack, 20 with a transverse loop formed by a carbon-pack ply coursing between said bar and blade, said mounting means including a pivotal support for one end of said blade and a catch for releasably holding the other end of said blade, said blade being swingable about its pivotal support, away from said bar, to facilitate the disposition between said blade and bar of said one carbon-pack 25 ply.
- 30 10. The combination with a platen over which a multiple-ply work-web, threaded into a carbon-pack, travels, said pack having two outer plies joined at the bottom by a fold, of a supporting bar fixedly connected at its ends to the 35 machine to parallel said platen, a carbon-pack-arresting blade co-operative with said fold, and means mounting said blade in juxtaposition to the platen-side of said bar, the outer one of said folded plies coursing between the blade and the 40 bar, said blade swingable away from said bar to facilitate the disposition of said carbon-pack ply between said blade and bar, said mounting means including a catch on said bar in which the free blade-end is deflectably held.

JESSE A. B. SMITH.

45
